STRING SUPPORTED SPINNING TOY

Robert Ruf, 9923 S. Winston Ave., Chicago 43, Ill.

Filed Feb. 26, 1964, Ser. No. 78,792

Term of patent 7 years

(Cl. D34—15)

FIG. 1 is a view in perspective of a string supported spinning toy, showing my design;

FIG. 2 is a front elevational view with the string twisted, ready for operation;

FIG. 3 is a face view of the disc of the toy, taken on the plane of the line 3—3, looking in the direction of the arrows;

FIG. 4 is an elevational view of the back side of the disc of FIG. 3;

FIG. 5 is a top plan view of the disc of FIG. 3;

The essential features of the design are the widely spread strings, diverging at the two handles, and passing through the central disc at two spaced points, the handles with saw cuts at each end for the strings, and the widened

rim of the central disk and central thin part of the disk, all of which is cut away by forming a pair of parallel holes in the disk at diametrically opposite points cutting away the rim and part of the thin part of the disk.

I claim:

The ornamental design for a string supported spinning toy, as shown and described.
